UNITED STATES PATENT OFFICE.

IKE BIVINS, OF INDEPENDENCE, KANSAS.

KILN.

Application filed February 26, 1923. Serial No. 621,216.

To all whom it may concern:

Be it known that I, IKE BIVINS, a citizen of the United States, residing at Independence, in the county of Montgomery and 5 State of Kansas, have invented certain new and useful Improvements in Kilns, of which the following is a specification.

This invention relates to improvements in kilns and particularly to a kiln for firing 10 clay ware.

An object of the invention is to provide a kiln in which the ware receiving compartment has a maximum capacity, and wherein the heating structure is placed at one side 15 thereof.

The invention further comprehends the provision of a specially built heating structure having an inclined wall above the fire box for directing the heat over the baffle between the fire box and the ware compartment laterally into said compartment.

The invention also includes the provision of an observation opening in the inclined wall above the fire box through which the 20 condition of the ware may be determined at all times.

The details of construction and arrangement of the parts to carry out these and other objects is clearly brought out in the 25 following description and claim, and shown in the accompanying drawings, in which;

Figure 1 is an elevation of the portion of a kiln including the heating structure, 30 which is located at one side.

Figure 2 is a sectional view taken on line 2—2 of Fig. 1.

1 indicate a kiln having a dome-shaped roof 2 and ware compartment 3, with the 35 heating structure 4 disposed at one side of the compartment 3.

This heating structure includes a front 5 for the fire box 6 which supports one end

of the grate 7 and is formed with an arched opening 8 to provide free access to the ash 45 pit 9. A baffle 10 forms the back of the fire box carries the rear end of the grate, and divides the fire box from the ware compartment. An opening 11 in the front having an arched top portion and sides inclined as 50 indicated at 12 to provide strength, communicates with the fire box to permit the charging and working of the fire. Above the fire box the heating structure is provided with an inclined wall 13, having a fire 55 resistant lining 14, which directs the heat into the ware compartment through the opening 15 over the baffle. An observation opening or peep hole 16 is formed in the inclined wall in line with the opening 15 so that conditions in the ware compartment may be observed from time to time to determine the 60 progress of the process being carried on in the kiln.

The heat striking the inclined wall 13 is 65 directed laterally into the ware compartment which is advantageous to secure a more uniform distribution of heat in said compartment, and consequently a more uniform temperature, the heat being directed 70 into the compartment in the central portion.

What is claimed is:

In a kiln, a pottery chamber having a top, an inclined arch extending to a point adjacent the upper end of the pottery chamber, a front wall having an opening therein arranged below the arch, a fire box below the arch, and a vertical baffle wall arranged between the fire box and the pottery chamber and extending above the opening, the 75 crown being provided with a horizontally arranged sight opening above the baffle wall.

In testimony whereof I affix my signature.

IKE BIVINS.
